Arthur L. Brown.
ATTORNEY.

UNITED STATES PATENT OFFICE.

ANDREW A. KRAMER, OF KANSAS CITY, KANSAS.

EAVES-TROUGH CONSTRUCTION FOR SHEET-METAL BUILDINGS.

1,258,914.

Specification of Letters Patent. Patented Mar. 12, 1918.

Application filed December 2, 1916. Serial No. 184,579.

To all whom it may concern:

Be it known that I, ANDREW A. KRAMER, a citizen of the United States, residing at Kansas City, in the county of Wyandotte 5 and State of Kansas, have invented certain new and useful Improvements in Eaves-Trough Constructions for Sheet-Metal Buildings; and I do declare the following to be a full, clear, and exact description of 10 the invention, such as will enable others skilled in the art to which it appertains to make and use the same, reference being had to the accompanying drawings, and to the letters and figures of reference marked 15 thereon, which form a part of this specification.

My invention relates to sheet metal buildings, and more particularly to buildings having side wall members, one of which 20 may constitute a downturned part of a roof member that extends in vertical alinement with the side walls, the principal object of the invention being to provide an effectual joint for the alining members.

25 It is also an object of the present invention to combine with such alining members a suitable drain or eaves trough.

In accomplishing these objects I have provided improved details of structure the 30 preferred forms of which are illustrated in the accompanying drawings, wherein:—

Figure I is a perspective view of a portion of a sheet metal building containing my improvements and equipped with an 35 eaves trough in accordance with the present invention.

Fig. II is a sectional perspective view through the roof and side wall of the building, illustrating the locking arrangement 40 of a trough therewith.

Fig. III is a perspective view of a modified form of joint and trough construction.

Fig. IV is a sectional view through the roof and wall sections, showing another 45 modification of the joint and trough.

Fig. V is a similar view illustrating a modification of the construction shown in Fig. IV.

Referring more in detail to the drawings:—

1 designates a sheet metal building of ordinary construction comprising roof sections 2 and side wall sections 3 having box joints 4; the roof sections having downwardly curved ends 5 in vertical alinement

60 with the side sections 3 and permanently fixed thereto by plates 15 to form the side walls of the building, the said plates being located along the inner faces of the wall sections and secured thereto by bolts and nuts 16—17.

65 Located at the outside of the side wall is an eaves trough 7, which may extend entirely around the building if it is so desired, but which is here shown only along one side; the said trough comprising a vertical outer wall 8 a horizontal base 9 and a back plate 10, the latter having an offset portion forming a shoulder 11 which projects between the side and roof members of 70 sections and has a vertical flange 12 adapted to fit snugly against the inner faces of the downturned members of the roof sections.

In order to secure the trough in position 75 to lock the roof and wall sections securely together at the same time, I provide the connecting plate 15 which extends longitudinally along the joint of the roof and side walls and overlies the inner flange 12 80 of the trough, the bolts 16 projecting through the lower edge of the plate 15, whereby the plate is securely fastened to the lower wall sections, and through the upper edge of the plate, through the trough 85 flange 12, and through the downturned ends 5 of the roof sections to join all the parts secured together.

I also preferably provide the outer wall 8 of the trough with a rolled head 8' which 9 stiffens and strengthens the trough and prevents its kinking while being assembled with the wall sections.

With this construction it will be seen that the trough may seat tightly against the 95 lower wall sections and that the offset portion of the back trough wall securely supports the trough between the sections so that it may catch all moisture that may drip from the upper sections. It is also apparent that the plate 15 not only serves to anchor the roof and wall sections together, and secure the trough in place, but also substantially stiffens the building walls.

It is apparent also that the exterior form 105 of the trough or drain may be modified as desired without departing from the invention, the forms here shown, however, being preferable on account of their simplicity.

In the modified form of trough shown in 110

Fig. III, the base 9 is located between the roof and body wall sections to support the trough as is done by the shoulder 11 in the preferred construction, the inner wall of the 5 trough lying along the inner face of the side of the building and having its upper edge downturned to form an anchor plate 15 and to receive the bolts 16 to anchor the parts together as in the previous case.

10 Fig. IV illustrates another form of trough consisting of a single piece of metal bent on itself to form an upturned outer wall 20, which extends inwardly between the roof and wall sections and has laterally turned 15 ears 21-22 for receiving bolts 23 whereby the trough is anchored in position to catch the drip from the roof sections.

15 Fig. V shows the same trough in an inverted position adapting it for use as a 20 weather strip or the like.

Assuming the trough to be so constructed, it will be seen that it may be easily installed by the ordinary workman, that it provides a water-proof joint and that the 25 back plates 15, when attached as described, substantially stiffen the building and enhance the appearance of the structure.

Having thus described my invention what I claim as new therein and desire to secure by Letters-Patent, is:—

1. A sheet metal building comprising side wall and roof sections, the latter having downturned ends coöperating with the wall sections, a drain member located along the exterior of the wall and comprising a vertical back member extended between the roof and wall sections, a plate overlapping the adjacent ends of the roof and wall sections on the inner faces thereof and anchor members extended through said plate, trough, 35 roof and wall sections for the purpose set forth.

2. A sheet metal building comprising side wall and roof sections, the latter having downturned ends coöperating with the side 45 walls, an eaves trough comprising a vertical back wall having a longitudinally extending, offset shoulder seated between said roof and wall sections, and a plate secured to the trough and to the wall sections for anchoring the said trough to said roof and wall sections.

In testimony whereof I affix my signature.
ANDREW A. KRAMER.
